UNITED STATES PATENT OFFICE.

HAROLD S. ASHENHURST, OF CHICAGO, ILLINOIS, ASSIGNOR, BY MESNE ASSIGNMENTS, TO INSULEX CORPORATION, OF CHICAGO, ILLINOIS, A CORPORATION OF DELAWARE.

INSULATED ROOF.

Application filed February 16, 1925. Serial No. 9,641.

My invention relates to roofs for buildings and has for its objects to provide novel means for insulating such roofs and a novel method of installing the insulating material.

6 It is a well-known fact that a large percentage of the heat loss in a building results from radiation through the roof, and that in order to avoid such loss, the roof should be suitably insulated, preferably with 10 a material that may be conveniently and economically installed either before, after or during the erection of the roof structure.

In order to accomplish the desired result, I have devised a roof and a method of installing the same in which a cellular insulating material is poured in place. The insulating material employed is preferably that disclosed in my prior Reissue Patent No. 15,952, dated November 25, 1924, in which the major 20 constituent is gypsum, the cellular structure being formed by combining gas-evolving chemicals with the gypsum. The resulting structure is extremely light.

The invention will be more readily understood by reference to the accompanying drawings, in which;

Fig. 1 is a sectional view through a roof showing the insulating material partly installed according to the preferred method.

30 Fig. 2 is a similar view showing partial insulation according to another desirable method, and

Fig. 3 is a sectional view on the line 3—3 of Fig. 1.

35 In the drawings, I have illustrated inclined rafters, 10, resting upon a side wall, 11, of any desired construction. In this instance, the plates 12 constitute the bottom wall of the space within which the insulating material 40 is received. In the construction shown in Fig. 1, the roof boards, 13, are rested upon and secured to the top edges of the rafters, the installation of the boards being completed to the upper extremity of the roof before the insulation is applied. Shingles, 14, are shown as a final covering, but other forms 45 of roofing material may be employed. Preferably a layer of waterproof paper, 14^a, is located beneath the roof boards.

50 Secured to the inner faces of the rafters are wood strips, 15, the vertical elevation of the strips being determined in accordance with the depth of insulation required. Thin boards or sheets, 16, are next laid on the strips.

I have found that the so-called plaster board, 55 commonly in use, is most suitable for this purpose. By carrying the outer sheeting, 17, up to the roof boards and by the use of strips, 18, and 19, and a narrow vertical section of plaster board, 20, the wall head space may 60 be insulated if desired.

In the insulation of a roof as shown in Fig. 1, the roof boarding may be completed and the shingles 14 or other weatherproof covering may be added. A sheet of plaster 65 board 16 is then laid on the strips, 15, at the lower end of the insulating space. In this condition, the insulating material is prepared by adding to the dry material a quantity of water sufficient to produce a plastic, easily 70 flowing mass, and is then poured into the space above the plaster board. The substance immediately expands or rises and sets within a reasonable time. Thereafter other plaster board sections are placed successively in 75 position and the operation of pouring the material is repeated until the space is filled to a point fairly close to the ridge pole. The remaining space at the top may be filled with pre-cast blocks of the same material if de- 80 sired. By this process, the insulation may be installed in previously completed roofs.

If, however, it is found more desirable to pour the insulating material from above the roof, the arrangement may be made accord- 85 ing to the illustration in Fig. 2, in which the plaster boards are installed to the upper extremity of the roof and the roof boards and shingles are placed in position in successive operations, a narrow portion at a time, the insulating material being poured into position following the completion of each separate portion. In either case, it will be found de- 90 sirable to pour only a small volume of the plastic mass at one time, allowing it to rise 95 and set before a successive pouring takes place. By reducing the hydrostatic pressure, the expansion will be greater, the material will be more cellular and the insulating effect will be more pronounced.

I do not wish to be limited to any particular form of insulating material, except as the same may be specifically claimed. I prefer, however, to use a material formed by mixing with water a dry mixture comprising 100 pounds of calcined gypsum, 3½ ounces of commercial retarder, 6¼ pounds of a suitable carbonate, such as calcium carbonate, and 105

12½ pounds of aluminum sulphate containing its water of crystallization, all of such ingredients being finely ground and thoroughly mixed in a dry state.

5 The material so formed and comprising gypsum as its principal ingredient is when set highly cellular, weighing only about 12 pounds per cubic foot, and it has been found to serve very effectively for insulating the 10 roof with respect to sound and heat and also for fireproofing the roof.

The thickness of the monolithic body of insulating material is determined by the location of the strips 15. Where the rafters are 15 relatively shallow, and where a thick body of insulation is desired, it may be found desirable to attach the plaster boards directly to the under surfaces of the rafters, filling the entire space between the supporting plaster 20 boards and the roof boards with the insulation. For all ordinary practical purposes, however, this is unnecessary, ample insulation being secured by providing a thickness of two to four inches of the cellular material.

25 In the preceding discussion, I have not attempted to describe the various modifications that will necessarily be employed in carrying out the invention under different circumstances, the scope of the invention being determined by the claims. For example, the 30 word "rafters" is used to designate structural elements whether of wood or of metal, and the word "boards" to designate confining elements, whether of plaster board, metal sheets, 35 wood boards or flexible sheets such as tough waterproof paper.

While in ordinary cases it will be found desirable to pour the insulation in a step-by-step process, this may be varied, the form 40 elements being completed to the full height desired, and the insulation poured into a space left open at the crown of the roof, the space being completely filled at one time or in successive operations to permit the setting of 45 one batch before the next is poured.

The steps will be varied somewhat in insulating different kinds of roofs, for example, conical, ogee, hip, mansard and gable roofs.

In some instances, permanent roof boards 50 may not be used, nailing strips being located at the required intervals for use in attaching the roofing.

It will be understood also that I may in some cases insulate inclined roofs only part 55 way to the crown then carry the insulation across to form the ceiling of a room.

Where a previously built roof is to be in-

sulated, to its full height from the inside, it will be found difficult to pour the material to fill the space at the top and this space may be 60 filled with pre-formed blocks as described in my co-pending application, Serial No. 9,640, filed of even date herewith.

A feature of novelty and utility in the roof as here disclosed is that it is not only effectively insulated but is substantially fire-proof, even if constructed with wood rafters. The monolithic body of cellular mineral insulation is firmly sealed between the rafters and will protect them even though the roofing is 70 destroyed. Furthermore, no sparks or embers may drop into the building and start an interior fire. Where the structural elements are steel, and plaster boards are used for confining the mineral insulation, the roof is 75 completely fireproof.

Inasmuch as the insulating and fireproofing material is very light, weighing, if desired, only 12 pounds or less per cubic foot, the roof load is not materially increased and complete 80 protection may be secured at a very reasonable cost.

I claim:

1. A roof comprising in combination rafters in spaced relation, a weatherproof covering secured to said rafters at their upper faces and held by said rafters substantially against vertical movement with respect thereto, sheet-like means secured to said rafters underneath the weatherproof covering and 90 in spaced relation to said weatherproof covering, and a light porous monolithic body hardened in highly cellular form in the enclosed space between the rafters in close contact with the surfaces of the weatherproof covering and the other space defining parts and extending into all the irregularities of 95 such surfaces.

2. The method of providing insulation in a frame roof structure, which comprises applying sheet-like closure means to the rafters underneath the weatherproof covering and in spaced relation thereto, and then completely filling the enclosed space with a light porous monolithic body of highly cellular insulating material produced in such space by the setting and hardening of a quantity of material poured into such space as a free-flowing plastic mass containing a high percentage of 100 entrapped gas.

Signed at Chicago, Ill., this 13th day of February, 1925.

HAROLD S. ASHENHURST.
